Attorney

UNITED STATES PATENT OFFICE.

JOHN B. MASERANG, OF BELLEVILLE, ILLINOIS.

MAIL-BOX SIGNAL.

Application filed February 16, 1927. Serial No. 168,784.

This invention relates to new and useful improvements in mail boxes, and particularly to signals therefor.

One object of the invention is to provide a signal, which is adapted to be operated into and out of signaling position by the postman, and which will be visible from the road, or from the home of the owner.

Another object is to provide a main signal, for indicating to the owner the presence of mail in the box, and supplemental signal means, for indicating to the postman the presence of mail, in the box, to be collected.

Another object is to associate the main and supplemental signals so that, when the main signal is moved into or out of signaling position, and the supplemental signal is in signaling position, such supplemental signal will be moved to non-signaling position, without separate manual operation.

Other objects and advantages will be apparent from the following description when taken in connection with the accompanying drawing.

25 In the drawing:

Figure 1 is a perspective view of a mail box, showing, in full lines, the main signal in elevated position, and the supplemental signal in non-signaling position, and showing, in dotted lines, the main signal in non-signaling position, and the supplemental signal in signaling position.

Figure 2 is a sectional detail view showing the supplemental signal in elevation.

35 Figure 3 is a vertical sectional detail view, taken on the line 3—3 of Figure 1.

Referring particularly to the accompanying drawing, 10 represents a mail box of the type in general use in rural districts.

40 Secured to opposite sides of the box, at a suitable distance rearwardly of the door 11, are the vertical supports 12, and pivotally mounted on one of the supports is a lever 13, and on the other support there is a pivotally mounted an angle lever 14. Secured to and extending between the levers is a metal plate 15, the ends of which extend in parallel relation to each other, longitudinally of the box, when this main signal is in elevated position, said plate serving to give a clear view thereof from the road, as well as from the home of the owner, which latter may be located at a considerable distance from the road. Pivots connected to 55 the other arm of the angle lever 14, is an

end of a horizontal operating link 15', said link extending beyond the door, when the main signal is in lowered, or non-signaling position. Secured to the side of the box, a short distance rearwardly of the door 11, 60 is a vertical guide bracket 16, in which the forward end portion of the operating link 15' is slidably disposed, a transverse pin 17 being disposed in the lower portion of the bracket for interchangeable engagement in 65 the notches 18, in the lower edge of said link, and whereby to hold said link in its adjusted positions. On the side of the box, in rear of the bracket 16, is a vertically channeled member 19. Pivots mounted on the 70 operating link 15' is the arm 20, of the supplemental signal 21, said arm being provided with a laterally extending tab 22 which is adapted to engage with the upper edge of the link, to prevent said arm falling 75 too far when dropping into non-signaling position, and whereby said supplemental signal arm will be associated with the link 15' in such manner that said arm will be moved therewith. The portion of the arm 20, inwardly of the pivot thereof, is adapted to be engaged in the channel of the member 19, whereby to hold said arm in a vertical signaling position. Secured to the outer end 80 of the arm 20 is a right-angularly bent metal 85 plate 21, which serves as a flag to be seen from the road, as well as from the home of the owner of the box, and is for the purpose of indicating to the postman, that there is mail in the box to be collected. 90

When the main signal is in non-signaling position, the link 15' is in its forwardly projected position, with the pin 17 engaged in the rearmost notch of said link, whereby to maintain the main signal against being 95 blown out of its position, by the wind. Also, this serves to maintain the arm 20 properly engaged in the channeled member 19, to hold the signal in elevated position. When it is desired to elevate the main signal, the postman grasps the forward end of the link 15', raises the link in the guide bracket, and then pushes the link rearwardly, with the result that the levers 13 and 14 will be swung into vertical position, displaying the signal plate 100 15 to view from the road and from the owner's house. When the owner has mail to be dispatched, he places the mail in the box, lifts the link 15', and then swings the arm 20 until its lower end enters the upper end 105 110.

of the channel of the member 19, whereupon he permits the link to fall into its former position, causing the said end of the arm 20 to properly enter the channel, and remain in elevated signaling position. The pin 17 is properly engaged in the foremost of the notches of the link, whereby said link is maintained against accidental movement which would alter the position of the main signal.

What is claimed is:

1. A signaling device comprising a support, a main signal on the support, means for operating the signal into and out of signaling position, a supplemental signal carried and movable with the operating means, and means on the support for holding the supplemental signal in signaling position when the main signal is in non-signaling position, and for releasing the former when the latter is moved into signaling position.
2. A signaling device comprising a support, a main signal on the support, a link connected with said signal for operating the same into and out of signaling position, a supplemental signal movably carried by the link, and means on the support for engagement with the supplemental signal to hold the same in signaling position only when the main signal is in non-signaling position, said supplemental signal being releasable from said holding means, upon actuation of

said link to move the main signal into signaling position.

3. A signaling device comprising a main signal, a link pivotally connected therewith for moving the signal into and out of signaling position, a supplemental signal pivotally carried by the link, means for engaging the supplemental signal to hold the same in signaling position when the main signal is in non-signaling position, and means for guiding the link, said link being adapted to be moved pivotally to release the supplemental signal from the holding means.

4. A signaling device comprising a support, a main signal pivotally mounted on the support, a link pivotally connected with the signal and movable slidably to raise and lower the signal, a guide receiving the link therethrough, means on the guide for limiting the movement of the link in both directions, a vertical channel member adjacent the guide, and a supplemental signal pivotally carried by the link and arranged to engage an end in the channel member when the link is moved to main signal lowered position, said supplemental signal being adapted to gravitate into non-signaling position upon upward pivotal movement of the link, and means on the supplemental signal for engagement with the link to limit the pivotal movement of the former.

In testimony whereof, I affix my signature.
JOHN B. MASERANG.
